UNITED STATES PATENT OFFICE.

LOUIS VERDY, OF BICKNELL, INDIANA.

LOCK.

Application filed May 23, 1921. Serial No. 471,542.

To all whom it may concern:

Be it known that I, LOUIS VERDY, a citizen of France, residing at Bicknell, in the State of Indiana, have invented certain new Improvements in Locks, of which the following is a specification.

This invention relates to improvements in door locks, the object of the invention being to provide an improved door lock which 10 can be readily manufactured at small cost, which can be readily operated either by means of a key or by a knob, is very strong and durable, is not likely to get out of order, and which cannot be picked.

Another object is to provide an improved lock of this kind embodying a latch bolt which can be operated either by a knob or a key, and also embodying means to enable the latch bolt to be securely fastened when 20 either in engaged or disengaged position, and thereby prevent said bolt from being operated either by means of a knob or by means of a key, when this is desired.

Another object is to provide an improved lock of this kind embodying a knob operated latch bolt and key operated tumblers to lock or release the latch bolt, and also embodying a thumb slide by means of which the tumblers may be moved to and held in 30 release position.

Another object is to provide an improved lock of this kind embodying a plurality of adjustably mounted tumblers.

Another object is to effect improvements 35 in the construction of the key, whereby the same is provided with a plurality of removable and adjustable wards which may be arranged to correspond with any desired adjustment of the tumblers.

With the above and other objects in view, the invention consists in the construction, combination and arrangement of devices hereinafter described and claimed.

In the accompanying drawings:

Fig. 1 is an elevation of a door lock constructed and arranged in accordance with my invention, with one side of the casing removed, and showing the latch bolt in shot or engaged position and locked by the tumblers, and with the key removed.

Fig. 2 is a similar view of the same, partly in section, and showing the latch bolt in release position and locked in such position by the detent pin, and also showing

the tumblers held in release position by the 55 thumb slide.

Fig. 3 is a transverse sectional view of the same on the plane indicated by the line 3—3 of Fig. 1.

Fig. 4 is a longitudinal sectional view of 60 the same on the plane indicated by the line 4—4 of Fig. 1.

Fig. 5 is a transverse sectional view of 65 the same on the plane indicated by the line 5—5 of Fig. 2.

Fig. 6 is a similar view of the same on 70 the plane indicated by the line 6—6 of Fig. 1, showing the key in position to operate the tumblers.

Fig. 7 is a detail perspective view, partly 75 in section, of the case and the detent pin, and showing said pin in raised or release position.

Fig. 8 is a detail sectional perspective view of the lower portion of the lock case, 75 showing the stud plate for holding the lower ends of the tumbler actuating spring.

Fig. 9 is a detail sectional view of the key.

Fig. 10 is a detail sectional view of the 80 same, taken on the plane indicated by the line 10—10 of Fig. 9.

Fig. 11 is a detail elevation of the same at right angles to Fig. 9.

The lock case 1 is provided with a removable plate 2 and is also provided at the front or outer end with a flange 3 to be rabbeted in the edge of the door on which the lock is applied. The plate 2 has one end engaged under a flange 4 with which the case is provided and has the other end secured by a headed screw 5, which screw enters a threaded opening in a pivot stud 6 with which the lock case is provided, and which is preferably integral therewith.

A latch bolt 7 is mounted for longitudinal movement in the lock case and extends through an opening 8 in the front side of the case. A stud 9 projects from one side of the latch bolt and serves to limit the outward movement of the same. Said latch bolt has an opening 10 extending transversely therethrough and the opposing sides of which are convex, as at 11. A knob operated lever arm 12 extends through the opening 10 and has a sleeve or hub 13 which is mounted for turning movement in openings in opposite sides of the lock case,

as shown at 14 in Fig. 3. Said arm 12 has notches 15 in its rear side. Said notches are engaged by the hooked inner ends of coiled springs 16 which are arranged above 5 and below the latch bolt and the front ends of which are hooked to lugs 17 which are secured to the front end of the lock case by headed shanks 18. The said springs normally cause the arm 12 to hold the latch 10 bolt in engaged or shot position, as shown in Fig. 1 and Fig. 4.

The usual knob shank, not here shown, extends through a square opening 19 with which the hub or sleeve 13 is provided. In 15 the upper side of the latch bolt are openings 20, 21 to receive the lower end of a detent pin 22. When said pin is engaged in the opening 20 the latch bolt is secured in release position, as shown in Fig. 2, and the door 20 can then be freely opened or closed without reference to the lock. When the pin is engaged in the opening 21 the latch bolt is then 25 secured in locking position, so that the door is securely held locked, and the bolt cannot be operated either by means of a key or by means of the knob.

The said pin operates in an opening in the upper side of the lock case and also extends through annular bosses 23, 24 with which the 30 lock case is provided. The boss 23 has a semi-circular flange 25 and the pin has a correspondingly shaped flange 26. Said pin is rotatable, and when it is raised to entirely 35 disengage the latch bolt, the pin is then partly turned so as to cause the flange 26 to bear on the flange 25 and thereby hold said pin in such disengaged position. Before re-engaging the pin with one of the openings in the latch bolt, the pin must be turned to 40 cause its flange 26 to clear the flange 25 and the pin can then drop into engaged position with either of the holes, according to the position of the latch bolt. To limit the extent of the upward movement of the pin the same 45 is shown provided with a stop flange 27 near its lower end.

To control the operation of the latch bolt, I provide a plurality of key operated tumblers 28 which are pivotally mounted on the 50 stud 6 as shown, and are provided in their front sides with notches 29 to receive the rear or inner end of the latch bolt. Arms 30, 31 are thus formed above and below said notches, and are provided with beveled 55 shoulders 32 for engagement with beveled notches 33 in the rear end of the latch bolt. The said tumblers are provided on their lower sides with flanges 34 for engagement by the wards 35 of the key 36. These flanges 60 are of various widths and the tumblers are detachably mounted on the stud 6 so that they can be arranged as may be desired and the wards 35 of the key are detachable from the key shank and may be arranged therein 65 to agree with any desired arrangement of

the tumblers. The key shank has a bore 37 at its inner end and the wards 35 extend through a slot 38 in one side of the tubular portion of the key stem and have heads 39 to fit in the bore thereof. The wards are secured in the key stem in any desired arrangement by means of a screw 40, the shank of which is threaded in the bore of the stem.

The key-hole 41 is preferably provided only in the outer side of the lock case, so that preferably the key can be operated only from the outer side of the door. The tumblers are caused to engage their shoulders 32 in the notches 33 of the latch bolt by springs 42 which are here shown as coiled springs the upper ends of which are attached to the arms 31 of the tumblers, the lower ends of said springs being engaged with notched studs 43 which project from opposite sides of a stud plate 44, the said plate being secured by 45 screws 45 to the lower side of the lock case, as shown in Fig. 8.

In order to enable the tumblers to be turned to release position by a person within the room, and without the necessity of using a key, I provide a slide 46 which is mounted for sliding movement in the lower side of the case and which bears against the under side of the substantially semi-circular rear portion of the tumblers. The said slide has a 50 stem 47 which operates in a slot 48 in the lower side of the lock case and also has a thumb piece or nut 49 which is screwed on said stem and is preferably also secured thereto by a pin 50. When the slide is in the position shown in Fig. 1, it is entirely disengaged from the tumblers and the latter can only be operated and raised to release position by means of a key. When the slide is moved to the position shown in Fig. 2 it engages under the lower sides of the tumblers and serves to hold them in released position with respect to the latch bolt, as shown in Fig. 2.

While I have herein shown and described a preferred embodiment of my invention, I would have it understood that changes may be made in the form, proportions and construction of the several parts, without departing from the spirit of my invention, and within the scope of the appended claims.

What I claim is:

1. In a lock, the combination of a case, a bolt mounted for sliding movement in the case, a knob operated arm pivotally mounted in the case and engaged with the bolt, and a spring coacting with said arm to normally hold the bolt in shot position.
2. In a lock, the combination of a case, a bolt mounted for movement in the case, a knob operated arm pivotally mounted in the case and engaged with the bolt, a spring coacting with said arm to normally hold the bolt in shot position, and a detent element movable into and out of engagement with

said bolt and arranged to hold the same either in shot or in release position.

3. In a lock, the combination of a case, a bolt mounted for movement in the case and having a plurality of openings in one side, and a detent pin mounted for movement in the case to engage in either of said openings,

and also mounted for turning movement, said pin and case having coacting means to hold the pin in disengaged position when 10 said pin is turned in one position.

In testimony whereof I affix my signature.

LOUIS VERDY.
